(57) CLAIM

The ornamental design for a daisy table, as shown and described.

DESCRIPTION

FIG. 1 is a top plan view of the daisy table, showing my new design;

FIG. 2 is a bottom plan view thereof;

FIG. 3 is a front elevation view thereof;

FIG. 4 is a right side elevation view thereof;

FIG. 5 is a left side elevation view thereof;

FIG. 6 is a rear view thereof;

FIG. 7 is a top perspective view thereof;

FIG. 8 is a second top perspective view thereof;

FIG. 9 is a third top perspective view thereof;

FIG. 10 is a fourth top perspective view thereof;

FIG. 11 is a bottom perspective view thereof;

FIG. 12 is a second bottom perspective view thereof;

FIG. 13 is a third bottom perspective view thereof; and,

FIG. 14 is a fourth bottom perspective view thereof.

The broken lines depict portion of the daisy table that form no part of the claimed design.

1 Claim, 14 Drawing Sheets
